UNITED STATES PATENT OFFICE.

GUSTAVE LOUIS ANGE TARLÉ, OF MENETOU SALON, FRANCE.

BRIDGE SUPPORT.

Application filed March 15, 1920. Serial No. 365,980.

To all whom it may concern:

Be it known that I, GUSTAVE LOUIS ANGE TARLÉ, a citizen of the French Republic; residing at Menetou Salon, Cher, in the Republic of France, have invented certain new and useful Improvements in Bridge Supports; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 In the bodies of stringed instruments, usually the bridge rests with its whole length, or on two feet, on the belly of the instrument which supports it, giving rise to many inconveniences. The wider the belly of the instrument, the better the low notes are reinforced.

20 In the violin, where the belly is divided into two parts by an axial neutral zone, stationary or nearly so, the neutral zone being due to the fact that the movements are reversed from one side of the belly to the other, the belly loses its aptitude to reinforce the low notes since its effective vibration is really only equal to half the width of the belly.

25 To obtain the best possible tone from a violin for example, the belly should be without a neutral zone, and it should vibrate as a whole and not inversely in halves.

30 Further to obtain maximum compression and expansion of the air within the case, the arrangement should be such that the whole belly is raised in vibrating, the back should be pressed outwardly, and when the belly is depressed in vibration, the back should be pressed inwardly. Usually the belly and back of a violin are connected by a sound post, but since the neutral zone is present in the belly, the maximum effects of compression and expansion of the air within the case are not obtained since the belly vibrates inversely in halves as before mentioned. Further the belly is strained under the weight and tension of the strings. In 35 the sound post construction, the displacements of the back and the corresponding half of the body of a violin, or of the whole of the belly in the case of a mandolin, are parallel.

40 The air in the body does not undergo any compression or expansion in a mandolin,

(this fact explains the inaction of the sound post in this instrument).

To enable the invention to be fully understood it will now be described by reference to the accompanying drawings in which:

45 Figures 1, 2 and 3 show in longitudinal section, cross section and plan with the belly removed, respectively, a violin provided with a control system according to the prior invention before mentioned.

50 Figures 4 and 5 show in cross section and longitudinal section respectively on the line XX Fig. 5 and the line YY Fig. 4 the system of controlling the vibration of the belly and the back according to the present invention.

55 Figure 6 is a view of the underside of the rocking counter-bridge.

60 Figures 7 and 8 show in cross section and longitudinal section respectively on the line X'X' of Fig. 8 and on the line Y'Y' of Fig. 7 a modified method of control.

65 The earlier method of the applicant comprised a bar *a* or other undeformable frame arranged axially and longitudinally and secured in the blocks *b* by gluing or mortising and preferably being in the form of a body of uniform resistance and not entering into contact with the back *j* nor with the belly *i* of the violin. On this bar the applicant has attached under the belly, just below the bridge *c*, a counter-bridge *d* of shiftable shape such as is shown in Fig. 2 having two 70 feet so as to support the belly at two points immediately under the feet of the bridge.

75 The method according to the present invention consists in principle of combining the arrangement of the applicant's prior invention with the bridge employed in an ancient stringed instrument called a crouth. To this end, the belly *i* has a hole *e*, Figs. 4 and 5, at the point where one of the feet of the counter-bridge *d* makes direct contact 80 with the foot of the bridge through the hole, this latter being sufficiently large to avoid all contact with the belly. Further, the sound post *f* may be placed without inconvenience in a small socket *g*, Fig. 6, hollowed out in the under surface of the counter-bridge *d*, directly under the said foot of the bridge and the foot of the sound post is held in a small socket *h*, of annular shape, secured by glue to the back *j*. The bar *a*, at 85 the point where it supports the counter-bridge, is provided with an opening *k* which

is fitted with a blunt knife edge *l* of a hard substance, ebony, ivory or the like, on which the counter-bridge rocks, said counter-bridge having a groove *m* on its underside as shown in the drawing.

The bridge is thus supported by the interposition of the counter-bridge which operates as a pivot or axis and permits the bridge to vibrate in a precise rocking movement. Only one of the feet of the bridge touches the belly, the other controls the bottom through the sound post. Necessarily, the movements of the belly and the bottom are always inverse instead of being parallel. Further, the belly has no stationary neutral line, and will act like the bottom in this respect. The low tones will be improved and smaller instruments than usual may be made.

The pivot or axis of oscillation may be arranged directly under the bridge. To this end the belly *i* (Figs. 7 and 8) has a supplementary hole *o* in the axis of the bridge and in this case the bracket or bar *a* carries a pivot *p* passing through this hole without touching the belly and supporting the bridge *n* directly, which by reason of the small contact surface may be faced with a small plate *q* of hard material.

By means of this invention, which also relieves the belly, the sound bar may be reduced or done away with and the belly made thinner and more flexible.

Finally, the invention permits, after having obtained a bridge which vibrates continually and strongly by a free rocking movement about a pivot or an axis of support, of utilizing the movement once produced so that one of the feet of the bridge *40* raises the belly whilst the other through the sound post presses down the bottom and vice-versa; thus the air in the body is alternately compressed and expanded to the maximum degree, which gives the maximum brilliance. The great cause of irregularity of vibrations of the body is suppressed, the regularity of the vibrations of the bridge being assured; the neutral line of the belly being suppressed, the low notes *45* are improved, which allows smaller instruments to be made, the belly and the bottom not being weighted by the pressure of the bridge, may be made more flexible by thinning.

Having thus described the nature of the said invention and the best means I know of carrying the same into practical effect, I claim:—

1. In a stringed musical instrument and in combination, a belly, a back, sides con-

necting the belly and the back, a bridge having two feet, one foot mounted on the belly, the other foot passing through a hole in said belly without touching same, a counter-bridge arranged beneath said bridge and on the reverse side of the belly, one portion of said counter-bridge engaging the belly, another portion of said counter-bridge supporting the foot of the first-named bridge which passes through the hole in the belly, and means for pivotally supporting the counter-bridge independent of the belly and back.

2. In a stringed musical instrument and in combination, a belly, a back, sides connecting the belly and the back, a bridge having two feet, one foot mounted on the belly, the other foot passing through a hole in said belly without touching same, a counter-bridge arranged beneath said bridge and on the reverse side of the belly, one portion of said counter-bridge engaging the belly, another portion of said counter-bridge supporting the foot of the first-named bridge which passes through the hole in the belly, a bar secured longitudinally of the instrument supported at each end by the sides, a pivot on said bar, a recess in the counter-bridge for receiving said pivot and means for transmitting the vibration of the bridge to the back.

3. In a stringed musical instrument and in combination, a belly, a back, sides connecting the belly and the back, a bridge having two feet, one foot mounted on the belly, the other foot passing through a hole in said belly without touching same, a counter-bridge arranged beneath said bridge, and on the reverse side of the belly, one portion engaging the belly, another portion of said counter-bridge supporting the foot of the first-named bridge which passes through the hole in the belly, a bar secured longitudinally of the instrument supported at each end by the sides, a pivot on said bar, a recess in the counter-bridge for receiving said pivot, and a sound post secured to the counter-bridge and to the back of the instrument.

4. In a stringed musical instrument having a belly and a back, a bridge supported at one end on the belly, a support beneath the belly engaging the underside of the belly and also engaging the other end of said bridge and means to transmit the pressure of said other end of the bridge to the back.

In testimony that I claim the foregoing as my invention, I have signed my name.

GUSTAVE LOUIS ANGE TARLÉ.
